REFRIGERATING MECHANISM

John R. Reogle, Detroit, Mich., assignor to Cope-
land Refrigeration Corporation, a corporation
of Michigan

Application March 15, 1934, Serial No. 715,601

6 Claims. (Cl. 62—115)

This invention relates to refrigerating mechanism and particularly to a construction in which means are provided for dampening out audible vibrations of certain vibratory parts thereof.

5 Objects of the invention include the provision of means for dampening the vibratory movement of a part operatively connecting a vibratory element and a stationary element; the provision of an operative fluid connection between a vibratory element and a fixed element capable of permitting substantially unrestricted vibration of the vibratory elements but without itself vibrating at a rate which will be audible to the human ear; and a fluid connecting device between a vibratory 10 member and a fixed member having a natural period of vibration sensible to the human ear and having a weight associated therewith so constructed and arranged as to modify its natural period of vibration to such an extent that any 15 vibrations set up therein are inaudible to the human ear.

Further objects include the provision of a refrigerating mechanism including a fixed condenser, a resiliently mounted compressor and a tube connecting the discharge side of the compressor with the condenser, the tube having means associated therewith so constructed and arranged as to modify the natural period of vibration of the tube to a rate of vibration inaudible to the human ear; to provide a refrigerating mechanism including a base having a condenser fixed thereto and a compressor resiliently mounted thereon, the compressor being connected to the condenser by means of a conduit having a natural rate of vibration audible to the human ear, and the conduit having a weight affixed thereto so modifying its natural period of vibration as to render vibratory movement of the conduit inaudible to the human ear.

40 The above being among the objects of the present invention, the same consists in certain novel features of construction and combinations of parts to be hereinafter described with reference to the accompanying drawing, and then claimed, having the above and other objects in view.

In the accompanying drawing which illustrates a suitable embodiment of the present invention and in which like numerals refer to like parts throughout the several different views,

50 Figure 1 is a side elevational view of a refrigerating unit.

Fig. 2 is a vertical sectional view taken on the line 2—2 of Fig. 1.

55 Fig. 3 is an enlarged sectional view of the

conduit connecting the compressor and condenser, taken on the line 3—3 of Fig. 1.

Certain types of refrigerating mechanisms include a refrigerating unit having a base upon which a motor compressor unit and a condenser are mounted so as to be capable of being applied to or removed from a refrigerator cabinet in unitary condition. The motor compressor unit includes rotating, and usually in addition reciprocating parts which, particularly when they are driven at relatively high speed as in modern constructions, are more or less subject to vibration due to various reasons. In order to prevent these vibrations from becoming noticeably apparent in the refrigerator cabinet, it is the customary practice to resiliently mount the motor compressor unit, as by floating it on springs, so that the effects of its vibratory movement are minimized in the cabinet itself.

It is, of course, necessary to connect the discharge side of the compressor with the condenser and this is usually done through the medium of a copper tube of sufficient length to permit it to yield to the vibratory movements of the motor compressor during operation without materially restricting the otherwise free movement of the motor compressor and without endangering breakage of the tube due to the vibration and bending which it is necessarily subjected to in connecting the vibrating part to the fixed part. 20 I have found in many cases, however, because of the shape which the connecting tube must assume in connecting the motor compressor with the condenser, caused by the arrangement of these two parts as necessitated by requirements 25 of space or design, that the tube has a natural period of vibration within the audible range of the human ear, and because of the fact that during operation of the refrigerating mechanism 30 it is constantly subjected to the vibratory movements of the motor compressor, it has a tendency 35 to and actually does vibrate at its natural period. I have found that the vibration of the tube in this manner is often apparent as a low but audible hum and its nature is such that it is often 40 difficult to determine that it is actually the source of a hum. I have further found that it is possible 45 to eliminate the audible effects of vibration of this connection tube by changing its natural period of vibration to one outside, and preferably below, a rate of vibration audible to the 50 human ear. The simplest and most economical method for effecting this result is to secure to the tube, preferably at a point intermediate its 55

ends, a weight of sufficient mass to effect the desired result.

Referring now to the drawing, there is illustrated a refrigerating unit including a base or support indicated generally at 8 comprising a pair of spaced L-shaped angle iron members 10 which are secured together in their spaced relation by means of a pair of spaced, opposed angle iron members 12 arranged in perpendicular relationship with respect to the foot of the members 10 and fixed to the upper surface thereof as by welding or other suitable means. Referring now to Fig. 1, a condenser 14 is fixedly mounted upon the left hand end of the base. Upon the central portion of the base a motor compressor unit, indicated generally at 16, is mounted by means of three studs 18 fixed therein and projecting downwardly through cooperating portions of the base 8 and about each of which a coil spring 20 is positioned to resiliently support the weight of the motor compressor unit 16 upon the base. Nuts 22 are preferably provided on the studs 18 below the base 8 in order to prevent complete disengagement of the motor compressor unit 16 from the base, particularly during shipment.

The motor compressor unit 16 includes a finned main portion 24 which serves as a casing for a suitable electric motor (not shown) and an associated portion 26 which includes a compressor mechanism (not shown) of any suitable design operatively connected to the electric motor within the portion 24 and hermetically sealed with the motor within the casing. A bracket 28 is shown secured to the left hand end of the unit 16 in Fig. 1 for the purpose of supporting a small electric motor 30 for driving the fan 32 provided for causing a circulation of air through the condenser 14. In the particular construction shown, the unit 16, and particularly the compressor portion 26 thereof, is shown as being provided with a refrigerant discharge connection 34 which is connected by means of a tube 36 with the inlet or upper end of the condenser 14. The tube 36, as indicated in Figs. 1 and 2, extends to the left, as viewed in Fig. 1, into the plane of the fan 32 and then, as indicated in Fig. 2, is bent into a ring-like form encircling the periphery of the fan 32 in order to obtain proper length thereof, and then is again bent to the left to make connection with the condenser 14. Preferably, in order to reduce the stress in the tube 36 due to the relative vibration between opposite ends thereof, the main portion of the tube is flattened as best indicated in the sectional view of Fig. 3.

From the above description it will be apparent that in the construction described and shown, the condenser 14 is fixedly mounted upon the base 8 and the motor compressor unit 16 is resiliently mounted thereon so as to enable it to vibrate relative to the base. The tube 36 being relatively long because of its having been bent into a circle as described, will be of such flexibility, taken as a whole, as to offer no substantial restriction to the otherwise free vibratory movement of the unit 16. The end of the tube 36 connected to the unit 16 will, however, during operation of the mechanism, vibrate directly with the vibratory movement of the unit 16 and this will have the effect of vibrating the tube 36 as a whole and, under certain conditions at least, will set the tube 36 vibrating at its natural period of vibration. When the natural period of vibration of the tube 36 is within the audible range of the human ear 75 it is obvious an audible hum or sound will result.

As previously explained, I have found that if a weight of the required mass is affixed to the tube 36 at the proper location the natural period of vibration of the tube 36 will be modified and if the weight is of the required mass the natural period of vibration of the combined tube and weight will be outside of the range audible to the human ear. Such a weight is indicated at 40 and may be constructed of any desired material and secured in any suitable manner to the tube 36. 10 It may conveniently be formed of brass and soldered to the tube 36. While the particular position of the weight 40 may vary considerably, it will be found most effective for a given weight if it is secured substantially midway between the 15 point of connection of the tube 36 with the unit 16 and with the condenser 14. When such a weight is affixed to the tube 36 any audible vibration of the tube 36 will be completely eliminated and, inasmuch as one of the most desirable characteristics of present day refrigerating mechanisms is freedom from sound or noise, the present invention will be found to have considerable merit in this connection.

Formal changes may be made in the specific embodiment of the invention described without departing from the spirit or substance of the broad invention, the scope of which is commensurate with the appended claims.

What is claimed is:

1. In combination, a vibratable device, a substantially non-vibratable device, a fluid connection between said devices, said connection having a natural period of vibration within a range audible to the human ear, and a mass secured to 35 said connection intermediate the ends thereof of modifying said natural period of vibration thereof to a frequency outside of the range of vibrations audible to the human ear.

2. In combination, a rigid base, a device fixed 40 to said base, a device subject to vibrations during operation resiliently mounted on said base so as to permit movement thereof independently of said base, a fluid connection between said devices fixed at opposite ends thereto, and a weight secured to 45 said connection between the ends thereof limiting the natural period of vibration of said connection and weight to a rate outside of that audible to the human ear.

3. In a refrigerating mechanism, in combination, a rigid base, a condenser fixed thereto, a compressor device supported on said base for relative movement with respect thereto, a tube connecting said compressor device and condenser, and a weight so constructed and secured to said 50 tube as to confine the natural period of vibration of the combined weight and tube to a range outside of that audible to the human ear.

4. In a refrigerating mechanism, in combination, a rigid base, a condenser fixed thereto, a compressor device supported on said base for relative movement with respect thereto, a tube connecting said compressor device and condenser, having a natural period of vibration within a range audible to the human ear, and a weight secured to 60 said tube between the ends thereof of such mass as to limit the natural period of vibration of the weight and tube to a range beyond that audible to the human ear.

5. In a refrigerating mechanism, in combination, a rigid base, a condenser fixed thereto, a compressor device supported on said base for relative movement with respect thereto, a tube including a looped portion connecting said compressor device and condenser having a natural 70 75

period of vibration within a range audible to the human ear, and a weight secured to said tube between the ends thereof of such mass as to limit the natural period of vibration of the weight and tube to a range beyond that audible to the human ear.

5. In a refrigerating mechanism, in combination, a rigid base, a condenser fixed thereto, a compressor device supported on said base for rel-

ative movement with respect thereto, a tube including a looped portion connecting said compressor device and condenser, and a weight fixed to said tube approximately midway between the ends thereof and of such mass as to limit the natural period of vibration of the combined tube and weight to a range outside of that audible to the human ear.

5

JOHN R. REPLOGLE.
